TWO-STROKE INTERNAL COMBUSTION
ENGINE

Harry Ralph Ricardo, London, England

Application November 3, 1939, Serial No. 302,760
In Great Britain November 2, 1938

2 Claims. (Cl. 123—72)

This invention relates to high speed two-stroke internal combustion engines having one or more exhaust ports in the head of the cylinder and scavenging ports in the wall of the cylinder which are uncovered by the piston therein towards the end of its outstroke, the passages through which the scavenging air flows leading to these ports from a scavenging air belt to which air is delivered by a displacer pump. This pump comprises a cylinder with a piston therein which is reciprocated by a link which connects it to the engine crankshaft so that the pump is driven at crankshaft speed.

An object of the present invention is to provide a construction of the above-mentioned displacer pump and the means of operating it so that a certain desired phasing relation, as described hereunder, may be obtained between the working piston and the pump piston and a compact design of engine can be obtained together with other advantages indicated hereunder. A further object is to combine with such an arrangement means whereby any backflow or tendency to backflow of exhaust gases from the working cylinder into the scavenging belt, when the ports in the wall of the cylinder begin to be uncovered, may be prevented or materially reduced.

According to this invention the piston of the pump is guided and supported by and reciprocates on a fixed rod which runs right through the piston to the ends of the pump cylinder. This rod also takes the angular thrust of the link through which reciprocation is imparted to the pump piston from the connecting rod of the working piston, friction between the piston and cylinder and wear of the pump cylinder by the piston, such as would otherwise tend to occur, being thus obviated or lessened. With this construction of displacer pump there is combined a mechanically operated valve, preferably of the rotary type, which is arranged and operates to cut off the pump and close the transfer passage through which air is delivered by the pump to the scavenging belt approximately at the end of the delivery stroke of the pump piston whereby a charge of air under a pressure, substantially above the mean pressure existent throughout the scavenging period, is trapped in the scavenging belt and that part of the transfer passage which lies between the valve and the scavenging belt. The displacer pump while being driven at crankshaft speed is so out of phase with the working piston that the pump piston begins its delivery stroke at or about, and preferably shortly before, the commencement of the scavenging period and ends

this stroke after the scavenging ports have been closed by the working piston. Conveniently the valve not only controls the commencement and termination of the delivery of air from the pump into the transfer passage, but also controls the commencement and termination of the inflow of air to the pump cylinder during the suction stroke of the piston therein.

The pump cylinder is disposed with its axis approximately at right angles to the axis of the working cylinder and the crankshaft axis. Owing to the construction above indicated and in particular the means for guiding the pump piston, it is possible to position the displacer pump so that its axis lies in a horizontal plane at one side of the crank case in a manner which contributes to a compact design of that part of the engine. The valve, if of the rotary type as is preferred, may be arranged above the displacer pump with the transfer passage running past the valve from the pump cylinder to the scavenging belt.

The accompanying drawings illustrate by way of an example an engine construction provided with a displacer pump embodying the present invention. In the drawings, Figure 1 is a vertical sectional view of the improved engine showing the working cylinder, crankshaft and pump cylinder, the section being taken normal to the crankshaft axis and through the axis of the pump cylinder. Figure 2 is a longitudinal section through the rotary valve controlling the pump suction and delivery, the section being taken on the line 2—2 in Figure 3 looking in the direction of the arrows, and Figure 3 is a sectional end elevation showing the manner in which the rotary valve and certain auxiliaries are driven from the crankshaft. These drawings show the invention as applied to an engine operating with compression ignition, but it is to be understood that the use of the invention is not confined to engines of that type.

The two-stroke engine here shown has the following principal features. In the head A of the cylinder B is a combustion chamber C of the "open" type into which at the end of the compression stroke there is forced by the piston as much of the air charge as is practicable from the constructional point of view. In this combustion chamber is an exhaust port controlled by a poppet valve D. As will be seen the combustion chamber is conveniently situated centrally and coaxially with respect to the cylinder B and the exhaust port is similarly disposed centrally and coaxially in what may be regarded as the inner wall C' of the combustion chamber. The inlet ports E are

formed in the wall of the cylinder B, the latter being conveniently constituted by a liner inserted as shown in an outer water jacket casing B¹. The cylinder may, however, be formed otherwise. The 5 inlet ports are formed as passages E through what is preferably a thickened part B² of the wall of the cylinder or liner B, these passages leading to port openings on the inside of the cylinder from a scavenging air belt F which extends preferably completely round the outside of the cylinder B. The transfer passage G through which the air charge flows from the displacer pump cylinder H to the scavenging belt F is formed in the 10 wall or outer part of the crankcase G¹. However this transfer passage may be formed separately and arranged so as to lead to the scavenging belt F over the exterior of the crankcase.

The displacement pump comprises a cylinder H with a piston J therein. This cylinder is preferably formed integral with the crankcase G¹ though it may be separate and mounted on the crankcase. The cylinder H projects from the crankcase with its axis at right angles with respect to both the axis of the crankshaft K and the axis of the working cylinder B. The axis of the pump cylinder H lies in a horizontal plane situated somewhat below the horizontal plane in which lies the axis of the crankshaft K.

Extending right through the displacer cylinder 30 H from the outer end cover H¹ to the spider plate H², which lies over the inner end of the cylinder H, is a guide rod L¹. This may conveniently be formed hollow and fixed in place in the manner shown by the bolt L which extends not only through the spider plate H², but also through the cylinder cover H¹. The piston J slides on and is supported by this guide rod L which passes right through the piston. Thus this rod not only carries the weight of the piston, but also sustains 35 the angular thrust of a link M which extends from the piston J to some conveniently placed pivot pin M¹ on the big end of the connecting rod N of the working piston O.

This arrangement has several advantages. It 40 reduces the frictional loss arising from the reciprocation of the pump piston J and obviates wear of the cylinder H which would otherwise take place, and it enables the displacer pump to be designed and situated at the side of the crankcase so as to contribute to compactness in the 45 design of the whole engine. Weight and space can also be saved in that the piston J need not be so thick or extend as much in the axial direction as would be necessary if it was supported and guided 50 solely by the wall of the cylinder or by the use of one or more tail rods carried by the piston and extending right through one or both end covers of the cylinder.

In an engine thus constructed it is possible 55 to achieve a good compromise with regard to the dynamic balance of the engine. By arranging that the line of action of the centre of gravity of the reciprocating parts of the displacer pump lies approximately at right angles to the line of action 60 of the centre of gravity of the reciprocating parts associated with the main piston O, and by also arranging that the phase relation between the pump piston J and the working piston O is approximately 90°, a good balance may be 65 achieved.

This arrangement of parts, however, in the absence of a suitable timing valve, would make it impossible to arrange a satisfactory timing for the air transfer from the pump cylinder H to the 70 scavenging air belt F and thus into the cylinder B.

and would involve difficulties in connection with the scavenging cycle. Such a timing valve is preferably arranged as follows.

Above the pump cylinder H is a casing P which extends horizontally and contains a ported liner Q and within this the rotary timing valve R. The valve casing P like the transfer passage G is preferably formed integral with the crankcase J. In the valve casing P is the main air inlet P¹ controlled by the valve R with the passage which 10 leads to the port or ports H³ through which air is drawn into the cylinder H. The rotary valve R is driven in some convenient manner from the crankshaft K for example by means of a link extending between an eccentric on the crankshaft 15 and a crankpin on the end of the valve. One embodiment of this feature is illustrated in Figures 2 and 3 of the drawings and will be later described. The valve R controls not only the air drawn through the passages P¹ and port H³ into 20 the cylinder H, but also the delivery of this air after compression from the port H³ into the transfer passage G. This delivery of the air charge compressed in the displacer cylinder H takes place slightly before the commencement of 25 the scavenging period. The valve R cuts off the displacer cylinder H and closes that end of the transfer passage after the scavenging ports E have been closed by the working piston O. Owing to the phasing relation between the movements of the working piston O and of the piston J of the displacer pump and the timing effected by the valve R, there is trapped in the scavenging belt F and in that portion of the transfer 30 passage G which lies between the valve R and the scavenging belt F, air under a pressure substantially above the mean pressure existent throughout the scavenging period.

By the combination and arrangement of parts described it is possible to obtain a good compromise with regard both to the balance and functioning of the engine.

The arrangement by means of which the rotary valve R is driven will be seen by reference to Figures 2 and 3. The valve R is mounted on a 45 shaft R¹ so as to be rotatable therewith. On one end of this shaft R¹ is a crank pin R² which is engaged by one arm S of a cross-shaped link driven by an eccentric K² on the engine crankshaft K. This link has an arm S¹ extending laterally and oppositely to the arm S and serving to drive a dynamo and other auxiliaries as may be seen in Figure 3. An upwardly directed arm S² of the link engages a crank pin on the end of the valve-operating camshaft. A downwardly directed arm S³ drives an oil pump situated in the sump of the engine. The crank pin R² of the shaft R¹ which carries the rotary valve R also serves to drive through a drag link a water-circulating pump T.

With regard to the operation of the rotary valve R, this cooperates with ports Q¹ and Q² in the liner Q, these ports communicating respectively with the pump cylinder port H³ and the transfer passage G, while another part, not to be seen in Figure 1, communicates with the main air inlet P¹. In the valve R the part R³ seen in Figure 2 controls the delivery of air from the pump into the transfer passage. The parts R⁴ control the suction through the inlet pipe P¹ to 70 the pump.

What I claim as my invention and desire to secure by Letters Patent is:

1. In an internal combustion engine operating on the two-stroke cycle the combination of a cyl-

- inder, a piston therein acting on a crankshaft through a connecting rod, ports in the cylinder wall uncovered by the piston towards the end of its outstroke, through which ports scavenge air flows from a scavenge air belt around these ports, a pump comprising a cylinder and piston reciprocating therein, the pump cylinder being 5 mounted with its axis at right angles to and below the level of the crankshaft axis and approximately at right angles to the axis of the working cylinder, a guide rod extending through the piston and throughout the length of the cylinder on which rod the piston reciprocates, 10 the ends of this guide rod being rigidly carried by the ends of the cylinder, a transfer passage extending between the end of the pump cylinder and the said scavenge air belt, a valve located in the transfer passage adjacent to the pump, and 15 means for driving the pump from and at the same speed as the crankshaft but out of phase with the working piston.
2. In an internal combustion engine operating on the two-stroke cycle the combination of a cylinder, a piston therein acting on a crankshaft through a connecting rod, ports in the cylinder 20
- wall uncovered by the piston towards the end of its outstroke, through which ports scavenge air flows from a scavenge air belt around these ports, a pump comprising a cylinder and piston reciprocating therein, the pump cylinder being 5 mounted with its axis at right angles to and below the level of the crankshaft axis and approximately at right angles to the axis of the working cylinder, a guide rod extending through the piston and throughout the length of the cylinder 10 on which rod the piston reciprocates, the ends of this guide rod being rigidly carried by the ends of the cylinder, a transfer passage extending between the end of the pump cylinder and the said scavenge air belt, a valve located in the transfer 15 passage adjacent to the pump, and a link connecting the pump piston to the connecting rod of the working piston for driving the pump from and at the same speed as the crankshaft but out of phase with the working piston. 20
